UNITED STATES PATENT OFFICE.

LEONARD ALDRIN, OF DENVER, COLORADO.

REAMER FOR ROTARY WELL DRILLS.

Application filed February 9, 1923. Serial No. 618,032.

My invention relates to boring tools of the type used in drilling wells and its primary object resides in providing a reaming tool for enlarging and truing holes produced by the action of a rotary drill bit, in which simplicity of construction is combined with efficiency and practicability in use.

Further objects of the invention are to provide an expanding reamer adapted for use in direct connection with a rotary drill bit and to provide as a constituent part of the tool, rotary cutters of novel form and design. Another object is to provide a simple and convenient method of securing the rotary cutters on the parts of the tool on which they are mounted, and still another object of the invention resides in the provision of a reamer of the above described character having means to facilitate its withdrawal from the hole in which it has been lowered, in case of cave-ins or other obstructions.

With the above objects in view my invention consists in the construction and arrangement of parts illustrated in the accompanying drawings in the several views of which like parts are similarly designated and in which

Figure 1 represents a partially sectional elevation of my improved reamer in association with a bit of a rotary well drill;

Figure 2, an enlarged composite view of the reamer in its operative relation to a bore produced by the bit to which it is attached, the portion of the view at the left side of an axial line being an elevation, and that at the other side of said line being a longitudinal section of the tool.

Figure 3, a transverse section taken on the line 3—3, Figure 2;

Figure 4, a similar section along the line 4—4, Figure 2;

Figure 5, a sectional view of the lower portion of one of the pivoted arms of the reamer, showing the cutter in elevation; and

Figure 6, a section taken on the line 6—6, Figure 5.

Referring more specifically to the drawings, the reference character A designates the reamer, B the drill bit with which it is connected, and C the hollow stem of the tool which is in operative connection with mecha-

nism for its rotation at the surface of the ground.

The drill bit which is connected at the lower end of the reamer in axial alignment therewith, consists of a tapering body having rotary cutters arranged at its lower end and upon its circumferential surface, its construction being more fully described in Patent No. 1,607,937, issued November 23, 1926.

The three aligned elements A, B and C of the tool are separably connected by screw-joints and the elements A and B have axial bores 25 and 26 in communication with the tubular stem C for the introduction of a pressure fluid which forces the cuttings produced in the operation of the tool, to the mouth of the bore. In order to facilitate the upward passage of the cuttings, the reamer and the bit are provided with aligned channels preferably formed at quadrant points of their circumference.

In the operation of the tool assembled as hereinbefore described, the reamer enlarges the hole D produced by the rotary bit, to the outside diameter of the well casing which in Figure 2 of the drawings has been designated by the letter E, but, while for reasons of simplicity and economy of operation, the above stated arrangement is preferred, it will be readily seen that if so desired, the reamer may be used separate from the drill bit and applied to the bore after the bit has been withdrawn.

The reamer which per se and in combination with the drill bit, is the subject of the present application, comprises a body or holder 5 bored and channeled as hereinbefore described, and having at its upper and lower ends respectively, a screw-threaded socket 6 and a screw-threaded tenon 7 for its attachment to the stem and the drill bit.

The body has at quadrant points intermediate of its channels 8, longitudinal recesses 9 to admit the cutting members which in the operation of the tool engage the surface of the bore as illustrated in Figure 2.

The cutting members each consist of an arm 10 pivoted at its upper end by means of a bolt 12 to move about a horizontal axis. The arm carries at its lower end, a rotary cutter 17 which in the operation acts upon the wall of the excavation by the rotary

movement of the tool, and it has in a slot 14 formed at a point nearer its pivotal axis, a roller 15 which when the tool is withdrawn from the bore engages the inner surface of the well-casing.

A leaf-spring 16 fastened at its upper end within the recess, engages the lower portion of the arm to forcibly and yieldingly maintain the cutter in engagement with the work.

10 The cutters each consist of a circular, peripherally beveled disk 17^a having a short shank 17^c which is peripherally grooved as at 17^b to admit pins 13 by which the cutter is rotatably secured at the end of the arm.

15 The beveled surface of the disk is spirally serrated to provide the slanting cutting edges 17^d which in the operation of the tool engage with the work as shown in Figure 2, when by the action of the spring upon the 20 respective arm the cutter is projected from the surface of the holder.

The shank 17^c of the cutter extends into a circular recess of the arm and is surrounded by two bushings 18 of anti-friction material, which being snugly fitted in the recess, are spaced apart to admit the pins 13 to the peripheral groove of the shank. The bushings which conjointly provide a bearing surface for the rotary cutters, reduce friction and are readily renewed in case of wear or breakage.

25 The pins 13 which secure the rotary cutters on the respective arms, are fitted in parallel bores which extend transversely to the 30 axis of rotation of the cutter and they are held in place by screw-threaded heads 13^a which engage with correspondingly tapped enlargements at an end of the bores.

35 The cutters are mounted on the arms so that in their operative position they extend 40 axially at an angle to the axis of the holder to engage at their beveled cutting faces with the bottom of the enlargement of the excavation while clearing the vertical surface of 45 the same, as indicated in Figure 2 of the drawings.

When by a rotary movement imparted to the holder, the cutters are caused to rotate in a direction opposite to the movement of 50 the holder, the slanting cutting edges at their beveled peripheral edges gradually cut into the earth from their outer ends inwardly and move the cuttings toward the center of the excavation.

55 The cuttings upon entering the peripheral channels 8 of the holder are forced upwardly to the mouth of the excavation by a pressure fluid introduced into the tubular stem from which the cutting element is suspended.

60 When, after the operation is completed, the tool is withdrawn from the excavation, the rollers 15 by engagement with the inner surface of the casing E, retract the arms 65 and the cutters at the lower ends thereof

into the recesses of the holder and thus permit of moving the tool upwardly with the minimum of frictional resistance.

The upper portion of the body or holder of the reamer above its recesses, is reduced 70 in diameter in two steps, and mounted at quadrant points of the reduced surfaces, are cutters 19 and 20 of the same form as those at the lower ends of the pivoted arms. The cutters 19 and 20 are, like the others, rotatably secured by pins 23 extending in peripheral grooves of their shanks and anti-friction bushings 24 are fitted in recesses into which the shanks extend, as before.

75 The cutters at the upper portion of the reamer are disposed within the cross-sectional area of the lower or body portion of the same so as to clear the inner surface of the well casing and their function in the 80 operation of the tool is to facilitate its withdrawal from the excavation in the event of earth or rock entering the bore as by a 85 cave-in, by cutting through the obstructive matter while the rotating tool is drawn upwardly by the operating mechanism with 90 which its stem connects.

95 It will be observed that when the reamer is operating as illustrated in Figure 2 of the drawings, the rollers and the cutters on the pivoted arms are the only parts projecting beyond the cylindrical peripheral surface of its body and that when it is withdrawn from the excavation the cutters are completely retracted within the respective recesses.

100 Having thus described my improved reamer in the best form at present known to me, I desire it understood that minor changes in the construction and arrangement of its parts may be resorted to so as 105 to adapt it for use in connection with different drilling tools and under varying conditions, without departing from the spirit of the invention.

110 What I claim and desire to secure by Letters Patent is:

1. A reamer for well drills comprising a body provided with a peripheral recess, a pivoted arm in the recess of the body, a cutter mounted upon the outer face of the arm 115 at an end thereof, to rotate about an axis at an angle to said face, and a spring acting upon the arm to yieldingly project the cutter from the body.

2. A reamer for well drills comprising a body provided with a peripheral recess, a pivoted arm in the recess of the body, an inwardly beveled circular cutter mounted upon the outer face of the arm at an end thereof, to rotate about an axis at an angle 120 to said face, and a spring acting upon the arm to yieldingly project the cutter from the body.

3. A reamer for well drills comprising a body provided with a peripheral recess, a 125

pivoted arm in the recess of the body, and an inwardly beveled circular cutter mounted upon the outer face of the arm at an end thereof, to rotate about an axis slanting from the horizontal when the arm is in its normal operative position.

4. A reamer for well drills comprising a

body having means for attachment to a drill stem and having steps successively decreasing in diameter as they approach said means, ¹⁰ and rotary cutters mounted on the steps.

In testimony whereof I have affixed my signature.

LEONARD ALDRIN.
